UNITED STATES PATENT OFFICE.

MARIAN F. SZUKALSKI, JR., OF MILWAUKEE, WISCONSIN.

FLEXIBLE DIAL MOUNTING.

Application filed June 25, 1923. Serial No. 447,647.

To all whom it may concern:

Be it known that I, MARIAN F. SZUKALSKI, Jr., a citizen of the United States, and resident of Milwaukee, in the county of Milwaukee, and State of Wisconsin, have invented certain new and useful Improvements in Flexible, Dial Mountings; and I do hereby declare that the following is a full, clear, and exact description thereof.

This invention relates to mountings for dials such as those used on radio panels and is particularly directed to a flexible mounting.

In radio panels it frequently happens that the shafts which project therethrough are not exactly at right angles to the face of the panel. Consequently a dial mounting thereon in the usual manner produces an unsightly appearance and frequently necessitates a remounting of the apparatus.

In addition to this the shafts are sometimes not straight with reference to the axis of the rotary portion and consequently the dials have unequal spacing from the panels at different portions of a revolution.

This invention is designed to overcome the above noted defects, and objects of such invention are, therefore, to provide a flexible dial mounting which will at all times hold the dial lightly against the panel face irrespective of any lack of alignment of the shaft, which is so constructed that the dial may be positioned and secured upon the shaft after the apparatus is assembled, and which will cause the dial to bind against the panel with a light spring pressure to prevent undesirable shifting after the device has been set.

An embodiment of the invention is shown in the accompanying drawings, in which:

Figure 1 is a sectional view through the dial and the adjacent portion of the panel, such view corresponding to a section on the line 1—1 of Figure 2.

Figure 2 is an inner face view of the dial with the shaft shown in section and with parts broken away to more clearly illustrate the construction.

Figure 3 is a sectional view on the line 3—3 of Figure 2.

The dial comprises an annular ring 1 of any of the usual insulating materials, and is provided with a circular recess 2 upon its inner face and with an inner shoulder or rim 3. The extreme inner face of the dial is thus an annular flat ring 4 (see Figures

1 and 2). The adjusting knob 5 may be a hollow conical member as shown, and is provided with a threaded connection 6 with the dial 1, as may be seen from Figure 2. The knob may be of any desired material such as the usual insulating material employed in constructing dials.

A centrally positioned hub 7 is provided and is equipped with a set screw 8. This hub carries a spring spider having a plurality of radially extending spring arms 9, which project outwardly and tend to remain in a plane at right angles to the axis of the hub. These spring arms have their outer ends received in recesses 10 formed in the annular shoulder 3 of the dial, as may be clearly seen from the sectional view shown in Figure 3.

It is to be noted that the spaces 10 or 73 notches are of a slightly greater depth than the thickness of the spring fingers 9 of the spider, the purpose of this will hereinafter appear. These spring arms are held in position by means of a ring 11 which may, if desired, be of metal. This ring seats against the annular shoulder 3 and is held in place by counter-sunk screws 12.

In applying the dial to the apparatus, the adjusting knob 5 is removed and the hub 7 is slipped over the shaft 13 which freshly projects from the front panel 14. Thereafter, the hub is moved inwardly along the shaft 13 a slight distance so as to slightly flex the spring finger 9 thus holding the annular face 4 of the dial flatly against the outer surface of the panel 14 by a light yielding pressure. The set screw 8 is tightened and the adjusting knob 5 is then screwed in place thus housing the interior parts.

In using this dial it will be found that although the shaft 13 may be slightly out of its correct position and may not project outwardly exactly at right angles with reference to the face of the panel, that nevertheless the dial will lie flatly in contact with the face of the panel in all positions of adjustment. This is due to the peculiar mounting of the dial for the spring arms or finger 9 will give sufficiently to allow the dial to accurately conform to the face of the panel.

The slightly greater depth of the notches or cut out portions 10 in the annular shoulder 3 allows the outer ends of the spring finger 9 to slide inwardly and out-

wardly to a slight extent as the dial adjusts itself during rotation to correct for errors in alignment of the shaft 13 thus providing the utmost freedom for the automatic adjustment of the dial.

It will be seen that a flexible dial mounting has been provided which is eminently suited for radio panel equipment, which may be quickly attached to a projecting 10 shaft, which has no exposed metallic parts, and which will accurately compensate for errors in alignment of the shaft.

Although one form of the invention has been described in considerable detail, it is 15 to be understood that the invention may be variously embodied and is, therefore, to be limited only as claimed.

I claim:

1. In a radio apparatus, the combination 20 of a panel, a shaft projecting outwardly therefrom and a dial comprising an annular member, a manually operated portion projecting outwardly therefrom and a resilient connection between said dial and said 25 shaft tending to urge said dial towards said panel.

2. A dial for radio apparatus comprising a disk like member having a hollow central portion, a hub located within said central 30 portion and resilient means connecting said hub and said dial.

3. A dial for radio apparatus comprising a disk like member having a hollow central portion, an adjacent knob extending out-

wardly therefrom, an annular portion projecting inwardly from said disk like portion, a hub positioned in axial alignment with, and interiorly of said dial, and resilient 35 radially extending fingers carried by said hub and secured to said dial.

4. A dial for radio apparatus comprising a disk like member having a hollow central portion, a hub located interiorly thereof and in axial alignment with said disk like member, and a plurality of resilient members 40 extending outwardly from said hub and carried by said dial and slidably related to said dial.

5. A dial for radio apparatus comprising a disk like member having a hollow central 45 portion, an adjusting knob detachably secured to said disk like member and projecting outwardly therefrom and having a centrally hollowed portion, a hub located interiorly of said dial and provided with a set screw, a plurality of radially extending 50 resilient fingers carried by said hub, said dial having notches formed interiorly thereof adapted to receive said radial fingers and to permit slight relative motion radially inwardly or outwardly, and a retaining ring 55 secured over said fingers and to said dial.

In testimony that I claim the foregoing I have hereunto set my hand at Milwaukee, in the county of Milwaukee and State of Wisconsin.

MARIAN F. SZUKALSKI, JR.
